UNITED STATES PATENT OFFICE.

HENRY W. CARTER, OF PROVIDENCE, RHODE ISLAND.

ABRADING-MACHINE.

1,177,483.

Specification of Letters Patent. Patented Mar. 28, 1916.

Application filed December 4, 1915. Serial No. 65,099.

To all whom it may concern:

Be it known that I, HENRY W. CARTER, a citizen of the United States, residing at Providence, in the county of Providence 5 and State of Rhode Island, have invented new and useful Improvements in Abrading-Machines, of which the following is a specification.

This invention relates to abrading machines and has particular application to a 10 rotary grinding machine.

The principal object of the invention is to provide a device of this character which is particularly adapted to the sharpening of 15 blades of any description, and which in addition thereto is capable of sharpening pencils.

Another object of this invention is to provide a device of this character which will 20 sharpen a pencil in the form of a perfect cone and without the liability of breaking the lead during the sharpening operation.

Further objects of the invention will appear as the following description is read 25 in connection with the accompanying drawings which form a part of this application, and in which:—

Figure 1 is a front elevation. Fig. 2 is a 30 vertical section of the same. Fig. 3 is a top plan view.

Referring to the drawings in detail, A designates the standards which comprise a pair of vertically extending members 1, which are arranged in parallel spaced relation and which are preferably formed of 35 metal. Connecting the lower ends of the vertical members is a plate 2 which is provided on one of its sides with laterally extending jaws 3 which are arranged in spaced relation. The lower jaw is provided with 40 a transverse opening which is adapted to threadably receive a thumb screw 4, the screw extending through the lower jaw and disposed between the lower and upper jaw.

45 The two jaws are adapted to form a bracket so as to receive any suitable support, the thumb screw adapted to hold the standard rigidly thereupon. Formed upon the medial portion of each of the vertical members 50 1 and connecting the same is a plate 5 which is provided with a transversely extending bearing 6. Journaled within the bearing is a shaft 7, one end of which is provided with a head 8, while the opposite 55 end is provided with a horizontally extending bore 9. It will be noted that one extremity of the shaft is mounted within the

bearing while the remaining portion of the shaft extends laterally from the standard of the side opposite to the side upon which the laterally extending jaws are formed. Rigidly mounted upon the shaft is a beveled gear 10 which is held in spaced relation to the standard A by means of a collar 11, the collar being provided with an annular flange which is adapted to engage the gear and which cooperates with a second collar 12 to hold the gear in proper spaced relation rigid upon the shaft. The bore 9 formed in the outer extremity of the shaft 70 is adapted to threadably receive a screw 13 which is provided with an enlarged head 14, the underside of the enlarged head adapted to abut the outer edge of the collar 12 whereby it will be forced into engagement 75 with the gear to hold the latter rigidly upon the shaft.

Formed integrally with the outer extremities of the standard and connecting the parallel members is a horizontally arranged bracket 15 provided with a bearing 16 at a point medially of the two vertically extending members of the standard, said bearing adapted to receive a vertically arranged shaft 17. This shaft 17 extends 85 above and below the bracket 15 and has rigidly mounted thereon a pinion 18, said pinion being arranged adjacent the underside of the bracket, and is adapted to mesh with the large bevel gear 10. The upper 90 extremity of the shaft 15 is provided with a frusto-conical shaped emery wheel 19, the wheel being held in spaced relation to the bracket by means of washers 20, while threadably mounted upon the upper extremity of the shaft is an inverted frusto-conical supporting member 28 which engages the upper face of the wheel. This member 28 is relatively smaller than the 95 emery wheel so that a sharpening surface 100 is presented between the lower edge of the member and the outer edge of the wheel.

It will be seen from this construction that upon rotation of the beveled gear and by means of a handle 22, rotary motion will be 105 embodied to the pinion 18, and the latter being rigidly mounted upon the shaft 17 will cause the emery wheel to be rotated above the bracket 15.

Referring more particularly to the bracket 110 15, the same is formed substantially T-shaped, the head portion thereof being indicated as at 23, and the stem as at 24. It will be noted that the head portion 23 is of

such a length as to extend beyond the lower edge of the emery wheel, the said extensions being provided on the upper face thereof with longitudinally extending grooves 25, 5 each of the grooves being substantially semi-circular in cross section. The stem 24 of the bracket is provided on its upper face with a longitudinally extending depression 26 which is substantially semi-circular in 10 cross section and which has its lower wall inclined upwardly toward the shaft 17 as indicated at 27, the depression being of such a length as to extend under the emery wheel and terminating at a point adjacent the 15 shaft 17.

When it is desired to use this device for the sharpening of blades of any description, the blade is placed within one of the grooves 25 so as to cause the cutting edge thereof 20 to lie at an angle to the surface of the emery wheel whereby upon rotation of the wheel through the medium of the pinion and bevel gear as has been described, the abrading surface of the wheel will contact 25 with the cutting edge of the blade and thereby cause the latter to be sharpened. It will be noted that the ends of the grooves 25 are open so as to permit the moving of the blade to be sharpened longitudinally 30 so as to present different sections of the cutting edge to the surface of the wheel.

In the sharpening of pencils, the pencil is placed within the depression 26 as shown 35 in Fig. 1 of the drawing, the bottom wall of the depression causing the pencil to engage the undersurface of the emery wheel. By exerting pressure upon the outer end 40 of the pencil, the end to be sharpened may be within full control of the operator, that is, by exerting more downward pressure upon the outer end of the pencil corresponding upward pressure will be transmitted to the opposite end whereby the pencil will be caused to engage the under 45 surface of the emery wheel at a corresponding pressure. In order to more effectively sharpen pencils the undersurface of the emery wheel has a surface of a coarser grade than that of the sides thereof. This 50 makes a very keen cutting surface for the pencil and causes the pencil to be quickly and neatly sharpened.

When it is desired to sharpen shears or the like the same are opened to their full 55 capacity whereupon the outside edge of one of the blades is laid flat against the side wall of the frusto-conical supporting member, the wall being of such an inclination as to cause the cutting edge of the blade 60 to contact with the top surface of the emery wheel at an angle corresponding to that of the side wall of the supporting member. Having placed the blade of the shear to the

emery wheel in the above described manner, the large gear is then rotated to cause 65 the rotation of the emery wheel, the direction of rotation being from left to right, or from the inside of the shears outward thereby causing the blade to be sharpened 70 with the usual beveled edge. Owing to the fact that the emery wheel rotates from left to right, any possible chance of producing a wire edge upon the blade is prevented.

From the foregoing taken in connection with the accompanying drawings, the construction and operation of my device will be apparent to those skilled in the art without further description, and that minor changes in size, shape, proportion and minor details of construction may be made without departing from the spirit and scope 80 of the appended claims.

What I claim is:

1. An abrading machine comprising a hollow rectangular standard, a clamping 85 bracket formed on the lower end of said standard, a transversely extending bearing formed at the medial portion of said standard, a shaft journaled in said bearing, a bevel gear rigidly mounted upon said 90 shaft and lying parallel to said standard, a vertically extending shaft journaled in the upper end of said standard and extending above and into said standard, a pinion keyed to the said vertical shaft and meshing with the bevel gear, an abrading 95 wheel rigidly mounted on the upper extremity of said vertical shaft, and an article supporting bracket formed on the upper end of said standard and disposed in 100 close proximity to the under surface of said wheel and extending beyond the periphery of said wheel.

2. An abrading machine comprising a standard, a shaft journaled in the upper 105 end of said standard and extending above the same, a frusto-conical shaped abrading wheel mounted upon the upper extremity of said shaft, a T-shaped bracket formed on the upper end of said standard and horizontally disposed thereon, said bracket disposed in close proximity to the underside 110 of said wheel and having its extremities extending beyond the periphery of the wheel, longitudinally extending grooves 115 formed on the upper face of the bracket, certain of said grooves being arranged substantially at a tangent to said wheel, the remaining groove extending beneath the wheel, and means for rotating said shafts. 120

In testimony whereof I affix my signature in presence of two witnesses.

HENRY W. CARTER.
